UNITED STATES PATENT OFFICE.

GUSTAVE A. SCHLECHTER, OF READING, PENNSYLVANIA.

DESIGN FOR A SPOON.

SPECIFICATION forming part of Design No. 21,239, dated December 15, 1891.

Application filed November 11, 1891. Serial No. 411,623. Term of patent 7 years.

To all whom it may concern:

Be it known that I, GUSTAVE A. SCHLECHTER, a citizen of the United States, residing at Reading, in the county of Berks and State of Pennsylvania, have invented and produced a new and original Design for Ornamenting Spoons, which is illustrated in the accompanying drawing, and clearly set forth in the following specification.

- 10 My design relates to the ornamentation of spoons, forks, and the like household articles; and its object is to impart to such articles a unique historical and memorial character.
- 15 The leading features of my design are the representations of a monument in a circular inclosure and a closed gate, from which a pathway leads to the monument. In the pathway are outlined two human figures. Trees and shrubbery are distributed about to produce a realistic effect. This constitutes the design for the bowl of the spoon. Upon the shank of the handle where it joins the bowl there is a representation of another monument. This monument is partially inclosed within a wreath of
- 20 ornamental work, which springs from the base on either side and extends from thence to the end of the handle in a series of ornamental curves and straight lines. Above the monument represented on the shank of the spoon
- 25 there is a panel extending along the narrow part of the handle of the spoon. Above this

ornamentation are two swords crossed, forming a part of the ornamentation of the widening portion of the broader part of the handle. Between the guards of these two swords and 35 arranged so as to appear to be resting upon them is a shield-shaped figure presenting an ornamental and attractive appearance. Upon the broadest portion of the handle and enclosed within the convolutions and curves of 40 the ornamentation are representations of the busts of two men, and above these is the outline of the figure of a keystone. The whole design is stamped or etched upon the surface of the spoon, so as to produce the effect of a 45 bas-relief.

In the drawing, A is the representation of a keystone; B B, the busts of two men; C', the shield; D, the ornamental panel; d d d, the ornamental curves and straight lines forming 50 the ornamental outlines of the handle; E, the monument on shank of the handle; F, the bowl of the spoon, with circular fence about a monument, with trees, shrubbery, and figures; G, the closed gate. 55

What I claim is—

The design for the ornamentation of a spoon herein shown and described.

G. A. SCHLECHTER.
